UNITED STATES PATENT OFFICE

JOHN H. THEISS, OF METUCHEN, NEW JERSEY

WRAPPING APPARATUS

Application filed January 30, 1931. Serial No. 512,295.

This invention relates to combined wrapping, taping and tape-severing machines and particularly to an improved apparatus for wrapping and sealing rolls of light sensitive motion picture film in a protective covering similar to that shown in my co-pending application S. N. 491,991, filed October 29th, 1930.

This invention aims to provide a novel apparatus for applying and sealing a protective covering for an object approximately cylindrical in shape. A further object is to provide such a machine, whose various functions may be safely and positively performed in a darkened room under the control of a relatively unskilled operator. An additional object is to provide such a machine that includes improved means for feeding and severing coated sealing tape. Another object is to provide such a machine that includes improved means for controlling the overlap of the applied tape. Additional and more specific objects will plainly appear from the detailed description presented herein—

To enable those skilled in the art to use my invention I will as an illustration describe a preferred method of carrying it into effect, with the understanding that modifications may be made and the invention embodied in different forms without departing from its spirit and scope in its broader aspects.

In the accompanying drawings—

Figure 1 is an end elevational view of the apparatus.

Figure 2 is a top plan view thereof.

Figure 3 is a vertical cross sectional view taken on the line 3—3 in Figure 2 showing an optional overlap signal.

Figure 4 is a vertical cross sectional view taken on the line 4—4 in Figure 3, showing a phantom view of the upper crimping member in its elevated position.

Figure 5 is a cross sectional view taken on line 5—5 in Figure 3.

Figure 6 is a diagrammatic plan view of the stripping device and of the tape-feeding and severing mechanisms in their retracted positions.

Figure 7 shows a similar view with the

severing plunger in its advanced position, after having severed the tape.

Figure 8 shows a similar view with the severing plunger again in its retracted position and with the stripping mechanism engaging 55 the end of the tape.

Figure 9 shows a plan view of a modified form of the severing plunger.

Figure 10 shows a side elevational view of the severing mechanism. 60

Figure 11 shows a side elevational view of the stripping rollers and the severing blade.

Figure 12 shows a vertical cross sectional view of one of the stripping rollers.

Figure 13 shows a top plan view thereof. 65

Figure 14 shows a plan view of a preferred form of the overlap control mechanism.

Figure 15 shows a vertical cross sectional view taken on line 15—15 in Figure 14.

Figure 16 shows a vertical cross sectional 70 view taken on the arc 16—16 in Figure 14.

Figure 17 shows a cross-sectional view taken on line 17—17 in Figure 3, showing an optional overlap signal.

A preferred form of my improved apparatus includes the rotatable support 20, mounted within a fixed crimping ring 21 and cooperating with the vertically reciprocating pressure plate 22 rotatably mounted in and supporting the upper crimping ring 80 23, as shown in Figure 3.

Associated with the support 20 is a device 24 to control the rotation thereof, shown in Figures 14 and 15.

Associated therewith is a tape-feeding 85 mechanism 26, shown in Figures 2 and 3. Cooperating therewith is a mechanism 27 for severing and stripping the sealing tape, shown in Figures 6 to 13 inclusive.

The apparatus is assembled on a base 28, 90 mounted on a suitable table 29. Fixed to the support 28 and surrounding the crimping ring 21, is an annular guard 57, which serves both as a protection for the operator and also as a guide for the flat circular sheets of 95 wrapping material, one of which is shown in its uncrimped position at 76A in Figure 4.

Attached to the periphery of the support 20 and projecting above the top surface thereof is an annular guide 70, adapted to confine 100

thereon a cylindrical object, such as a roll of motion picture film 77, under which is previously placed the sheet of wrapping material 75, as shown in Figure 3.

- 5 Fixed to the base 28 is the lower crimping ring 21, in whose lower portion is provided a housing 30, in which is fixed the bushing 31 and the vertically adjustable bushing 32. Rotatably and slidably supported within the 10 bushings 31 and 32 is the shaft 33, fixed to the support 20. The shaft 33 is resiliently supported by means of the spring 34 coacting with the retaining ball 35 and the shaft 36 within the bushing 32.
- 15 The spring 34 is designed to have sufficient power to press upwardly upon the shaft 33 with sufficient force to maintain the support 20 in an elevated position, so that its top surface is level with the rim 21A of the crimping 20 ring 21, whenever the support 20 is freed of the weight of the film 77, and is unsupported by the lever 41. The vertical movement of the shaft 36 is controlled by means of the slot 37 and the pin 38. On the end of the shaft 36 is fixed a disc 39, which bears upon the foot 40 of the lever 41. This lever is pivoted at 42 to the leg 48 of the table 29. The other end of the lever 41 is pivoted at 43 to the link 44. The link 44 is actuated by the depression 30 of the pedal 45 on the lever 46, pivoted at 47 to the leg 48 of the table 29. The lever 46 is pivoted at 49 to the link 44.

Fixed to the base 28 is the bracket 50, to 35 which is pivoted the lever 51. The rear end of the lever 51 is pivoted at 52 to the link 44 and supports the counterweight 52A, as shown in Figure 1. The forward end 53 of the lever 51 is forked to engage the groove 54 in the shaft 55. Fixed to the upper end of the shaft 55 is a weighted handwheel 56.

Fixed to the lower end of the shaft 55 is 40 pressure plate 22, which supports the upper crimping ring 23 and is rotatably mounted therein by means of the ball bearings 58.

The plate 22 is afforded slight vertical motion within the ring 23 by means of the elongated ball race 59. Fixed to the base 28 are two vertical guide rods 60, shown in 45 Figure 2. These guide rods pass through the annular projections 61, fixed to the periphery of the ring 23, so that the ring 23 is prevented from rotating but free to slide vertically on the guides 60.

50 The mechanism for positively controlling the rotation of the support 20 is shown in Figures 14, 15 and 16, and will now be described.

On the under surface of support 20 are a 55 series of hemispherical depressions 62, extending in mutual contact in a complete circle around the centre of the support 20. Rotated on the bushing 31 is an arm 63, carrying at its extremity the pin 64, which is adapted 60 to engage one of the depressions 62, when the

support 20 is depressed, in a manner which will be elsewhere described herein.

Mounted on the under side of the arm 63, is the T-slotted bracket 65, in which slides the pin 66. The projecting end of the pin 66 76 is adapted to slide in the spiral groove 67, contained in the circular plate 68, fixed to the base of the ring 21.

Surrounding the rotating collar 69, to which is fixed the arm 63, is the spiral spring 75 71, one end of which is attached to the arm 63, by means of the screw 72, and the other end of which is attached to the plate 68 by means of the screw 73.

The rotation of the arm 63, when engaged 80 with the rotatable support 20, causes the spring 71 to be energized thereby, so that when the pin 64 is released from the depression 62, by the elevation of the support 20, the energized spring will cause the sliding pin 66, to retrace its path in the groove 67 and in the T-slot of the bracket 65, and will thereby reverse the rotation of the arm 63 so that it will return to its initial position, 85 against the stop 74A. 90

The travel of the pin 66 in the slot 67 can be controlled by means of the adjustable stop 74, placed in the terminal portion of the slot 67, so that one complete revolution and a determined amount of overlap can be positively controlled thereby during the application 95 of the tape.

The tape-feeding mechanism is designated by the reference character 26, and is shown in detail in Figures 2 and 3, and will next be 100 described.

Surrounding the shaft 78, which is vertically mounted on the base 28, is the collar 79, supporting the disc 80 fixed thereto, and which is adapted to support thereon a tape 105 spool 81. The tape 99 comprises an adhesive coating on its inner side C and is obtained in this condition before the roll of tape is put on the spool 81.

The tape spool 81 is adapted to rotate freely on the shaft 78 and its speed of rotation is tensionally controlled by means of the washer 82, coacting with the spring 83 and the thumbscrew 84.

Fixed to the under side of the base 28 is the 115 bracket 85, containing two parallel guideways 86. Slidably mounted within the guideways 86 is the slide 87, containing the vertical housing 88. Fixed within the housing 88 is the vertical shaft 89, to which is 120 attached the collar 90 and the handgrip 91. Rotatably mounted on the collar 90 is the roller 92, free to rotate thereon by means of the ball bearings 93. Surrounding the periphery of the roller 92 is a cushioning tire 125 94, preferably made of gum rubber.

The slide 87 is freely reciprocated in the guides 86 by means of the handgrip 91 and is held in its advanced position, as shown in Figure 3, by means of the spring latch 95, 130

actuated by the spring 96. The latch 95 is supported on the under side of the bracket 85, by means of the bracket 97, which supports the latch shaft 98, as shown in Figures 3 and 5.

The mechanism for severing and stripping the adhesive coated sealing tape 99 is designated by the reference character 27, shown in Figures 6 to 13 inclusive, and in an assembled view shown in Figure 2, and is described as follows:

Similar portions of the upper crimping ring 23 and the lower crimping ring 21 are cut away to form an aperture 100, shown in Figures 2 and 10, to permit the application of the tape to the wrapped film when the upper and lower crimping rings 21 and 23 are in their engaged position.

Mounted on the lower crimping ring 21 near the forward end of the aperture 100, is the bracket 101. Slidably supported within the bracket 101 is the severing plunger 102, actuated by the handgrip 103 and held in its retracted position by means of the spring 104, one end of which is attached to the bracket 101 and the other end of which is attached to the projection 105 on the plunger 102.

The projection 105 also serves as a stop to limit the retraction of the plunger 102. The plunger reciprocates in the guideways 106, shown in Figure 10.

Mounted on the lower crimping ring 21, near the rearward end of the aperture 100, is the tape-severing blade 107, shown in Figure 10. The profile of the cutting edge of this blade is given an angular formation, in order to more readily penetrate the tape 99.

Mounted also on the base 28 and adjacent to the blade 107, is the bracket 108, supporting the upper stripping roller 109, rotatably mounted thereon and shown in Figure 11.

Rotatably mounted on the base 28, is the lower stripping roller 110, also shown in Figure 11.

The rollers 109 and 110 rotate upon and are each held in position by a screw, such as is designated at 111 in Figures 12 and 13. Surrounding each of these screws, and attached thereto, is a spiral spring 112, as shown in Figure 12, in such a manner that the free end 113, of the spring 112, projects through the opening 114 at the base of the roller 110 and is held in position by means of the stop 115.

The ends of each of the stripping rollers 109 and 110, are truncated at an angle, as shown in Figure 11, to facilitate in the passage of the tape 99, there-between.

After the rollers 109 and 110 have been rotated during the stripping operation, the spring 112 acts to return these rollers to their initial position, shown in Figure 11.

On the further end of the plunger 102, is

the lip 116, adapted to engage the coated side C of the tape 99.

When the tape 99 is in position to be severed, as shown in Figure 6, the plunger 102 is advanced by the operator until the lip 116 comes in contact with the coated side C of the tape 99, and forces the tape through the angular opening formed by the stripping rollers 109 and 110. As the tape is forced through this opening, it is also forced into contact with the blade 107, so that it is penetrated and severed thereby.

The lip 116 remains in contact with the severed end 117 of the tape 99, as shown in Figure 7. When the tape is forced through the opening between the rollers 109 and 110, the angular ends of the rollers 109 and 110 cause the tape to bend longitudinally until it passes the rear edge of the rollers 109 and 110, when it again assumes its flattened position, as shown in Figure 7.

When the plunger is retracted by means of the spring 104, the coated side C on the end 117 of the tape 99, is drawn into contact with the rear surface of the rollers 109 and 110 and adheres thereto, so that the lip 116 is stripped therefrom and so that the end 117 of the tape 99 remains in the position shown in Figure 8.

A modified form of the end of the plunger 102, is shown in Figure 9, wherein the blade 107 is adapted to pass between the two forked ends 118 and 119, of the plunger 102, and wherein the lip 121 is adapted to engage the severed end of the tape 117 and the lip 120 is adapted to engage the applied end of the tape 122, as shown in Figures 7 and 8.

An optional modification of the mechanism for indicating the revolutions of the rotatable support 20, is shown in Figures 3 and 17.

Rotatably mounted on the bushing 31 is collar 25, to which is fixed the arm 123 and the arm 124, as shown in Figure 3. Fixed to the end of the arm 123 is the vertically disposed pin 125, whose upper end 126 is adapted to engage one of the hemispherical depressions 62, on the under side of the support 20. The engagement of the pin 125 with the support 20, causes the arm 123 to rotate therewith around the shaft 33.

Mounted on the base of the crimping ring 21, is the bell 128 and the clapper 129, pivoted at 130 and coacting with the spring 131.

Fixed to the clapper arm 129 is the cam 132, adapted to engage the lower end 127 of the pin 125. Mounted on the opposite side of the ring 21 is the bracket 133, supporting the spring 134, adapted to engage the downward projecting pin 135 in the arm 124. When the arm 123 is rotated by means of its engagement with the rotatable support 20, the lower end 127 of the pin 125, after one complete revolution, travels over the cam 132, which depresses the clapper 129 and at 130

the same time permits an overlap to be added to the revolution already made. This overlap can be determined by the length of travel permitted by the cam 132.

5 After the pin 127 passes the terminal end of the cam 132, the spring 131 forces the clapper 129 into contact with the bell 128, thereby providing an audible signal indicating that one complete revolution and a 10 determined amount of overlap has been made.

At this point the pin 135 on the arm 124, has forced the spring 134 back into the position shown by dotted lines in Figure 17 at 15 134A, when the pin 126 is released from the depression 62 in the support 20, the spring 134 acting upon the pin 135 and the arm 124 will cause this arm and its connected arm 123 to return to their starting position shown in 20 Figure 17. The cam and clapper will also return from their depressed positions 132A and 129A.

Operation

25 With the pressure plate 22 held in its elevated position by the counter weight 52A, with the control device 24 in the position shown in Figure 14, with the support 20 held in its elevated position as previously 30 explained herein; and with the tape in the position shown in Figure 8, the following preferred sequence of operations may be performed:

(I) A sheet of wrapping material 75, 35 shown in Figure 3, is inserted by the operator within the annular guide member 57, so that it will rest upon the rotatable support 20.

(II) The operator then places the roll of 40 film 77 upon the sheet 75 and upon the support 20. The weight of the roll of film 77 overcomes the action of the spring 34 and forces the support 20 into its depressed position, shown in Figure 3, thereby causing one 45 of the recesses 62 on the underside of the support 20 to engage the pin 64 of the indicating mechanism, shown in Figure 15. The depression of the support 20 by the weight of the film 77 carries the sheet 75 into the 50 crimping ring 21, so that the sheet 75 is thereby crimped around the periphery of the roll 77.

(III) A second and similar sheet of wrapping material 76 is placed upon the top of the roll 77 in its extended position 76A, shown in Figure 4.

(IV) The operator depresses the foot treadle 45, shown in Figure 1, which acts upon the lever 47, the link 44 and the lever 51 to 60 lower the pressure plate 22 and the ring 23. This causes the ring 23 to crimp the sheet 76 around the roll 77 and over the previously crimped edge of the sheet 75. The plate 22 then rests upon the sheet 76 and the roll 65 77. The support 20 then bears the weight of

the roll 77 and the weighted plate 22. The roll 77 prevents the contact of the rings 21 and 23.

(V) At this point the tape-feeding mechanism is in the position shown in Figure 8, 70 wherein the tape 99 engages the feed roller 92 and the stripping rollers 109 and 110, so that the uncoated or fabric side F of the tape 99 engages the rubber tire 94 and so that the coated or gummed side G of the tape 99 engages the stripping rollers 109 and 110. 75

The slide 87, shown in Figure 3, carrying the roller 92 and the tape 99, as shown in Figure 8, is quickly advanced by the operator by means of the hand grip 91 so that the roller 92 and the tape 99 assume the position shown in Figure 2.

The quick advance of the slide 87 causes the feed roller 92 to travel along the tape 99 and strip it from the stripping rollers 109 and 110, so that the end of the tape 99 is forced through the aperture 100, so that its gummed side C comes in contact with the wrapped periphery of the roll 77, as shown in Figure 2. 80

(VI) With the pedal 45 still depressed, the operator grasps the hand wheel 56 and rotates the pressure plate 22, which causes the rotation of the film 77 and the support 20. This causes the tape 99 to unwind from the 85 spool 81 and permits the tape 99 to be applied around the crimped edge of the sheet 76 that overlaps the crimped edge of the sheet 75. 90

(VII) When the operator is unable to rotate the hand wheel further, by reason of the stop 74, previously described herein, the slide 87 is retracted by the operator by means of the hand grip 91, so that the feed roller 92 will travel along the tape 99 and assume 100 the position shown in Figure 6.

(VIII) The operator then actuates the severing and stripping mechanism, as previously described herein, which leaves the tape 99 in the position shown in Figure 8 105 and which permits the plunger 102 to assume its retracted position, shown in Figure 6.

(IX) The pedal 45 is released by the operator and the plate 22 and the ring 23 assume their elevated position, as shown in Figure 3. At the same time the lever 41 presses upward and acts upon the shaft 36, which is in contact with the ball 35 and the shaft 33, so that the support 20 bearing the wrapped and sealed roll of film 77 is forced into its elevated position wherein the top surface of the support 20 is level with the edge 21A of the ring 21. 115

(X) The operator then removes the wrapped and sealed roll of film 77 and the support 20 is held in its elevated position as previously explained. 120

The elevation of the support 20 releases the pin 64 from the depression 62 and the indicating mechanism, so that the arm 63 of 125 130

the rotation controlling device 24 assumes its starting position, as previously explained.

The apparatus is now ready to repeat the above described sequence of operations.

Having herein described a preferred embodiment of my invention, I do not desire to be limited thereto since it may be modified or embodied in different forms without departing from its spirit. It is expressly stated that this embodiment is illustrative only and that the invention is not limited to the materials, dimensions, and specific elements described, but comprises all the equivalents of the several cooperating features herein shown and described. Hence I desire to cover all forms and modifications within the language or scope of any one or more of the appended claims.

What I claim as new and desire to secure by Letters Patent is:

1. An apparatus for applying and sealing sheets of protective covering for an object, comprising in combination; a base; a support rotatably mounted thereon and adapted to receive said object between two of said sheets; a stop actuated by the rotation of said support for limiting the revolutions thereof; resilient means for automatically resetting said stop; an annular crimping member surrounding said support and associated therewith, so as to coact with a reciprocable annular crimping member to crimp said sheets over the periphery of said object; and means actuated by the rotation of said support for affixing sealing tape around the thus wrapped periphery of said object.

2. An apparatus for applying and sealing sheets of protective covering for an object, comprising in combination; a base; a support rotatably mounted thereon and adapted to receive said object between two of said sheets; an annular crimping member surrounding said support and associated therewith so as to coact with a reciprocable annular crimping member to crimp said sheets around the periphery of said object; means actuated by the rotation of said support for affixing sealing tape around the thus wrapped periphery of said object; and an automatic stop actuated by the rotation of said support for limiting the overlap of said applied tape.

3. An apparatus for applying and sealing sheets of protective covering for an object, comprising in combination; a base; a support rotatably mounted thereon and adapted to receive said object between two of said sheets; an annular crimping member surrounding said support and associated therewith so as to coact with a reciprocable annular crimping member to crimp said sheets around the periphery of said object; means actuated by the rotation of said support for affixing sealing tape around the thus wrapped periphery of said object; and an au-

tomatic stop actuated by the rotation of said support for limiting the overlap of said applied tape; and resilient means for automatically resetting said stop.

4. An apparatus for applying and sealing sheets of a protective covering for an object, comprising in combination; a base; a support rotatably mounted thereon and adapted to receive said object between two of said sheets; an annular crimping member surrounding said support and associated therewith so as to coact with a reciprocable annular crimping member to crimp said sheets around the periphery of said object; means actuated by the rotation of said support for affixing sealing tape around the thus wrapped periphery of said object; and an audible signal actuated by the rotation of said support for indicating revolutions thereof.

5. An apparatus for applying and sealing sheets of a protective covering for an object, comprising in combination; a base; a support rotatably mounted thereon and adapted to receive said object between two of said sheets; an annular crimping member surrounding said support and associated therewith so as to coact with a reciprocable annular crimping member to crimp said sheets around the periphery of said object; means actuated by the rotation of said support for affixing sealing tape around the thus wrapped periphery of said object; and an audible signal actuated by the rotation of said support for indicating one complete revolution thereof plus a predetermined overlap.

6. An apparatus for applying and sealing sheets of protective covering for an object, comprising in combination; a base; a support rotatably mounted thereon and adapted to receive said object between two of said sheets; an annular crimping member surrounding said support and associated therewith, so as to coact with a reciprocable annular crimping member to crimp said sheets over the periphery of said object; and means actuated by the rotation of said support for affixing sealing tape around the thus wrapped periphery of said object, including tape-feeding means slideably associated with said base, a tape-severing shear associated with said base and tape-stripping rollers cooperating with said shear and said tape-feeding means.

7. An apparatus for applying and sealing sheets of a protective covering for an object, comprising in combination; a base; a support rotatably mounted thereon and adapted to receive said object between two of said sheets; an automatic stop actuated by rotation of said support for limiting the revolutions thereof; an annular crimping member surrounding said support and associated therewith so as to coact with a reciprocable

- annular crimping member to crimp said sheets around the periphery of said object; means actuated by the rotation of said support for affixing sealing tape around the thus wrapped periphery of said object, including a tape-feeding slide associated with said base, a tape-severing shear associated with said base and tape-stripping rollers cooperating with said shear and said tape-feeding slide. 10
8. An apparatus for applying and sealing sheets of protective covering for a roll of film, comprising in combination; a base; a support rotatably mounted thereon and adapted to receive said roll of film between two of said sheets; an automatic stop actuated by the rotation of said support to indicate revolutions thereof; an annular member surrounding said support and associated therewith so as to coat with a reciprocable annular crimping member to overlap said sheets around the periphery of said object; a pressure plate rotatably mounted within said reciprocable crimping member; treadle operated means for reciprocating said plate, together with said reciprocable crimping member; a tape-feeding slide so associated with said base that the application of said tape to the wrapped periphery of said roll of film is effected by the rotation of said pressure plate acting upon said roll of film and said support; a tape-severing shear associated with said base and tape-stripping rollers cooperating with said shear and said tape-feeding slide. 20 25 30 35 40 45 50 55 60 65 70 75 80 85 90 95 100 105 110 115 120 125 130
9. An apparatus for applying and sealing sheets of a protective covering for a roll of film, comprising in combination; a base; a support rotatably mounted thereon and adapted to receive said object between two of said sheets; an automatic stop actuated by the rotation of said support to limit the revolution thereof; an annular crimping member surrounding said support and so associated therewith as to coat with a reciprocable annular crimping member to crimp said sheets over the periphery of said object; and means actuated by the rotation of said support for affixing sealing tape around the thus wrapped periphery of said object, including a tape-feeding roller slideably associated with said base, tape-severing means including a fixed blade and a plunger reciprocably associated with said base and tape-stripping rollers cooperating with said plunger to strip the severed end of said tape from said plunger and to engage said severed end until it is removed from said stripping rollers by the advance of said tape-feeding roller into its forward position. 10 15 20 25 30 35 40 45 50 55 60 65 70 75 80 85 90 95 100 105 110 115 120 125 130
10. An apparatus for applying and sealing sheets of protective covering for an object, comprising in combination; a base; a support rotatably mounted thereon and adapted to receive said object between two of said sheets; an annular crimping member to crimp said sheets over the periphery of said object; and means actuated by the rotation of said support for affixing sealing tape around the thus wrapped periphery of said object, including tape-feeding means slidably associated with said base, tape-severing means associated with said base, a blade adapted to penetrate the uncoated side of said tape and a reciprocable plunger adapted to engage coated side of said tape, and tape-stripping rollers cooperating with said severing means and said tape-feeding means. 10 15 20 25 30 35 40 45 50 55 60 65 70 75 80 85 90 95 100 105 110 115 120 125 130
- In testimony whereof, I have signed my name to this specification this 23rd day of January, 1931.
- JOHN H. THEISS. 85
